UNITED STATES PATENT OFFICE

109,690

DESIGN FOR A HEAD COVERING OR THE LIKE

Mark E. Atwood and Joseph Gordon Atwood, Wauwatosa, and William L. Armstrong, Milwaukee, Wis.

Application March 7, 1938, Serial No. 75,636

Term of patent 7 years

To all whom it may concern:

Be it known that we, Mark E. Atwood, Joseph Gordon Atwood, residing at Wauwatosa, and William L. Armstrong, residing at Milwaukee, in the county of Milwaukee and State of Wisconsin, have invented a new, original, and ornamental Design for a Head Covering or the like, of which the following is a specification, reference being had to the accompanying drawing forming part thereof.

In the drawing:

covering or the like in one wearing position; and Figure 2 is a plan view of one of the new head coverings or the like.

We claim:

The ornamental design for a head covering or the like, substantially as shown and described.

MARK E. ATWOOD.
JOSEPH GORDON ATWOOD.
WILLIAM L. ARMSTRONG.
